UNITED STATES PATENT OFFICE.

WILLIAM M. KUBON, OF MINNEAPOLIS, MINNESOTA.

MANIFOLDING SALES-BOOK.

SPECIFICATION forming part of Letters Patent No. 748,755, dated January 5, 1904.

Application filed November 6, 1903. Serial No. 180,019. (No model.)

To all whom it may concern:

Be it known that I, WILLIAM M. KUBON, a citizen of the United States, residing at Minneapolis, in the county of Hennepin and State 5 of Minnesota, have invented certain new and useful Improvements in Manifolding Sales-Books, of which the following is a specification.

My invention relates to improvements in manifolding sales-books for use in stores and other places where it is desired to make more than one copy of orders or other memoranda.

My invention consists particularly in improvements in that form of manifolding sales-books in which the sales-slips are secured at one end of a backing-sheet and a block, together with carbon sheet or sheets, secured at the opposite end of the backing-sheet; and it consists in an improved arrangement of cover 20 secured underneath said block and extending oversaid block and under said backing-sheet.

To this end my invention consists in the features of construction and combination hereinafter particularly described and claimed.

In the accompanying drawings, forming 25 part of this specification, Figure 1 is a perspective view of a sales-book embodying my invention, and Fig. 2 is a similar view of the book partially constructed.

In the drawings, 2 represents a backing-sheet, preferably of cardboard. Secured to one end of the backing-sheet, as by means of staples 3, are a series of sales-slips 4, the free ends of said slips terminating some distance 35 short of the opposite end of the backing-sheet. Secured to the end of the backing-sheet adjacent to the free ends of the sales-slips, as by means of staples 5, is a block 6, composed, preferably, of a series of narrow 40 strips of cardboard arranged one upon the other. I secure between the block 6 and the backing-sheet one end of a carbon-sheet 7 and one end of a flexible cover 8. The cover 8, as illustrated in Fig. 1, is carried over the block and underneath the backing-sheet 2 and is folded over the top of the sales-slips to form a loose flap 9. At the binding edge 45 of the book the flexible cover is preferably

secured to the backing-sheet by the ends of the staples 3. By having one end of the flexible cover carried over the block 6 and secured underneath said block the block itself is covered and protected and there is no exposed free end of the cover to be caught and torn. 50

In making the sales-books the practice is to make up wide books or blanks which comprise a plurality of sales-books, and an important advantage of my improved construction is that in cutting these blanks into books 60 the knife will not draw the end of the flexible cover away from the block, as is sometimes the case when there is an exposed edge of the flexible cover at the block.

Having now described my invention, what 65 I claim as new, and desire to secure by Letters Patent, is—

1. A sales-book comprising a backing-sheet, a series of sales-slips bound together and to one end of said backing-sheet, a block secured at the opposite end of said backing-sheet, a carbon-sheet supported at one end in connection with said block, and a flexible cover secured at one end underneath said block and passing over said block and underneath said backing-sheet, the opposite end of said flexible cover being secured to said backing-sheet at the binding edge of said sales-slips, and extending over said sales-slips to form a loose flap. 70

2. A sales-book comprising a cover supporting at one end a block and carbon-sheet, and at its opposite end a series of sales-slips, said cover being secured underneath said block, and passing around said block and underneath the sales-slips, and being secured underneath the binding edge of the sales-slips and extending over the same to form a loose flap. 75

In testimony whereof I affix my signature 80 in presence of two witnesses.

WILLIAM M. KUBON.
